AUGUST C. LINDEKUGEL, OF SPENCER, SOUTH DAKOTA.

VAPORIZER.

1,184,248.

Specification of Letters Patent. Patented May 23, 1916.

Application filed October 26, 1915. Serial No. 53,050.

To all whom it may concern:

Be it known that I, AUGUST C. LINDEKUGEL, a citizen of the United States, residing at Spencer, in the county of McCook 5 and State of South Dakota, have invented certain new and useful Improvements in Vaporizers, of which the following is a specification.

My invention relates to a vaporizer 10 nozzle or nebulizer particularly adapted for distributing fluid disinfectants, insecticides and the like.

It is one object of the invention to provide a device of this character which embraces a reservoir for holding both gaseous 15 and liquid fluids under pressure and simultaneously supplying the same in a regulated flow to a nebulizing nozzle.

Another object resides in the specific dis- 20 charging or atomizing tip of the nozzle. And a still further object resides in the needle valve arrangement for controlling the admixture of gaseous and liquid elements used in the spraying.

With the above and other objects in view, 25 I will now proceed to describe a specific embodiment of the invention as illustrated in the accompanying drawings in which:

Figure 1 is a side elevation, partly in section, of a vaporizer and nebulizer constructed according to my invention. Fig. 2 is a vertical section longitudinally through the control valve, and Fig. 3 is a similar section through the nozzle head.

In detail: The invention, as illustrated, 35 comprises the reservoir 1 having an outlet in which is threaded one end 2 of a nipple, the other end 3 of which is threaded into a T 4. The T 4, at its upper end, is provided with a bushing 5 interiorly threaded 40 into which is one end of a pipe 6 of smaller diameter than the bore through the nipple so as to provide an air passage between the pipe and nipple; the pipe 6 being of sufficient length to reach nearly to the bottom 45 of the reservoir 1 and draw liquid therefrom. One end of a pipe 7 is screwed into the outlet 8 of T 4 and connects with a passage 9 of a control valve casing 10. Also 50 pipe 6 connects by means of an elbow 11^a and nozzle 6^a with pipe 11 which, in turn, connects with passage 12 in valve casing 10, said passage 12 being parallel with passage 9 and therefore a turning plug 13 may 55 be provided with passages adapted to

register with passages 9 and 12 to control the outflow from pipes 7 and 11.

The nozzle head comprises a body 14 having passages 15 and 16 which are intercepted by the needle valve seats 17 and 18, 60 respectively, entering at an angle and which extend into a nozzle tip 19 having a conical inlet and outlet connected by restricted throat 20. The equally spaced drill holes 21 are provided around the outlet end of 65 the tip 19 and are for the purpose of reducing the vacuum at the tip to permit an easier and thinner efflux of the fluid in an atomized condition. These drill holes 21 are preferably substantially at right angles 70 to the walls of the conical outlet of the nozzle tip 19.

The needle valves 22 and 23 for seats 17 and 18, respectively, terminate in the threaded shanks 24 and 25 which extend 75 through stuffing box bushings 26 and 27, respectively, screwed into the nozzle head and holding the packing tightly against the shanks of the needle valves so as to prevent leakage. The needle valves may be adjusted 80 to permit the desired amount of fluid to pass thereby turning the knurled knobs 28.

The operation of the vaporizer is as follows: Fluid disinfectant is placed in the reservoir 1 through an opening controlled 85 by the member 29 without permitting the air in said reservoir to escape and pressure is thus then created within the said reservoir, the amount of such pressure being indicated by a suitable gage 30. The needle valves 22 and 23 are adjusted and the turning plug 13 rotated to that position wherein it cuts off flow. The passages 9 and 12 of the valve 10 are connected with the passages 16 and 15, respectively of the nozzle head 90 by pipes 31 and 32. The turning plug 13 is then rotated to the position wherein the fluid may flow through the passages 9 and 12 and the gaseous pressure will be emitted from the reservoir 1 through the nipple end T 100 and to the pipe 7 whence it will be fed to the needle valve 23. At the same time, the pressure within the reservoir 1 will force the fluid disinfectant or insecticide, as the case 105 may be, through the pipe 6 and to the needle valve 22 where both fluid and gas will become mixed by the action of the conical wall of the nozzle tip 19 and pass through the restricted throat 20 and thence outwardly in an atomized or nebulized con- 110

dition. It will be seen that, by the arrangement of the valve 10, both passages or pipes 7 and 11 are simultaneously controlled, and by the arrangement of this valve 10 and the 5 needle valves 22 and 23 perfect control of the vaporizer may be obtained at all times.

While, in the foregoing, I have described a specific embodiment of the invention, it is to be understood that variations and modifications 10 may be resorted to without departing from the spirit and scope of the invention as defined in the appended claims.

I claim:—

1. In a nebulizer or vaporizer, a nozzle 15 head, a nozzle tip receiving fluids from said head and having a restricted throat portion to thoroughly mix said fluids, and means for

eliminating the vacuum caused by the efflux of the fluids, substantially as described.

2. In a nebulizer or vaporizer, a nozzle 20 head, a nozzle tip receiving fluids from said head and having a restricted throat portion to thoroughly mix said fluids, and passages opening into said nozzle beyond said throat portion for eliminating the vacuum caused 25 by the efflux of the fluids, substantially as described.

In testimony whereof I affix my signature in presence of two witnesses.

AUGUST C. LINDEKUGEL.
